US00D901277S

(12) **United States Design Patent** (10) **Patent No.:** **US D901,277 S**
(45) **Date of Patent:** **** Nov. 10, 2020**

(54) **HANDLE**

(71) Applicant: **WHIRLPOOL CORPORATION**,
Benton Harbor, MI (US)

(72) Inventors: **Daniel Chow**, St. Joseph, MI (US);
Daniel V. Clements, St. Joseph, MI
(US); **Christopher A. Gregory**, St.
Joseph, MI (US); **Patrick J. Schiavone**,
Benton Harbor, MI (US); **Mark W.**
Schulz, Benton Harbor, MI (US)

(73) Assignee: **Whirlpool Corporation**, Benton
Harbor, MI (US)

(**) Term: **15 Years**

(21) Appl. No.: **29/588,793**

(22) Filed: **Dec. 22, 2016**

(51) LOC (12) Cl. **08-06**

(52) U.S. Cl.

USPC **D8/316**

CLAIM

We claim the ornamental design for a handle, as shown and described.

DESCRIPTION

FIG. 1 is a front perspective view of a handle of the present disclosure;

FIG. 2 is a top perspective view of the handle of FIG. 1;
FIG. 3 is a bottom perspective view of the handle of FIG. 1;
FIG. 4 is a first side perspective view of the handle of FIG. 1;

FIG. 5 is a second side perspective view of the handle of FIG. 1;

FIG. 6 is a top plan view of the handle of FIG. 1; and,
FIG. 7 is a bottom plan view of the handle of FIG. 1.
The broken lines depict portions of the article that form no part of the claimed design.

1 Claim, 3 Drawing Sheets
